UNITED STATES PATENT OFFICE

140,835

DESIGN FOR A PAIR OF FRAMES FOR SUN- GLASSES OR SIMILAR ARTICLE

Herman Zimmer, Brooklyn, N. Y., assignor to
Sun Glass Industries, Inc., Newark, N. J., a cor-
poration of New Jersey

Application May 13, 1944, Serial No. 113,581

Term of patent 14 years

(Cl. D57—1)

To all whom it may concern:

Be it known that I, Herman Zimmer, a citizen
of the United States, residing at Brooklyn, county
of Kings, State of New York, have invented a
new, original, and ornamental Design for a Pair of
Frames for Sunglasses or Similar Article, of
which the following is a specification, reference
being had to the accompanying drawing, forming
part thereof, in which

Figure 1 is a front elevational view of a pair of
frames for sunglasses or similar article showing

my new design the temples being omitted there-
from and also from Fig. 2 for convenience of
illustration;

Figure 2 is a back view thereof; and
Figure 3 is a top plan view thereof.

I claim:

The ornamental design for a pair of frames for
sunglasses or similar article, substantially as
shown and described.

HERMAN ZIMMER.
